PROTECTIVE ENVELOPE

Florence R. Krueger, Santurce, P.R.

Application January 6, 1948, Serial No. 679

9 Claims. (Cl. 2—268)

1

This invention relates to protective envelopes for cushioning pads, and more particularly to easily disengageable protective envelopes for cushioning pads secured to wearing apparel.

Various types of cushioning pads are used in garments, for example, shoulder pads in ladies' wearing apparel, as well as shoulder, hip, and knee pads in sporting goods, and shoulder pads in men's wearing apparel. It is common practice to sew, or otherwise permanently attach, certain types of cushioning pads into apparel, but these pads, being of relatively thick and porous material, are subject to accumulations of dirt, dust and perspiration, and dry very slowly when laundered. Various protective covers or envelopes for such pads have previously been suggested for permanent attachment to the garment, but when the garment was to be laundered, the protective covers, either with or without the shoulder pad, required cutting away from the garment, with the subsequent attendant necessity of restitching or resewing the cover for the pad back into the shoulder portion of the garment.

The present invention provides a protective envelope for a pad which is normally secured to sheet material, such as a garment, and which affords protection to the cushioning pad which is usually made of absorbent material. The envelope is secured to the garment pad without the necessity of sewing or stitching, and without auxiliary fastening means. According to the invention, the cover or protective envelope may be readily removed from the pad without removing the pad from the garment, so that the pad may be laundered together with the garment, and the laundering fluid may readily enter all parts of the interior of the cushioning pad. The envelope may then be re-attached and securely held to envelop the pad without stitching or sewing. The present invention is particularly useful as a protective envelope for shoulder pads commonly secured to ladies' garments, such as blouses, dresses, and the like, but it is also applicable with equal effectiveness to other types of cushioning pads, such as in sporting goods and men's garments. One of the objects of the invention is to reduce the frequent necessity for laundering or cleaning shoulder pads, and when the envelope of the invention is made of moisture- and dust-impermeable material, the opportunities for soiling the pad are greatly reduced, with consequent reduction in frequency and cost of laundering and upkeep of the garment to the owner or wearer.

A practical embodiment of the invention, to

2

which the invention is by no means limited, is illustrated in the accompanying drawing, in which:

Figure 1 is a plan view of a protective envelope enclosing a shoulder pad which is attached to the inside face of the shoulder portion of a garment;

Figure 2 is a cross-section taken on the line 2—2 of Figure 1;

Figure 3 is a plan view of the upper, or garment-engaging, face of the envelope, showing the slit or slot in the face of the envelope and partly revealing the inner pad, the fabric to which the pad is attached having been removed for purpose of illustration;

Figure 4 is a cross-sectional view showing an early step in the attachment of the envelope to the pad;

Figure 5 is a cross-sectional view similar to Figure 4, but showing a later step in the attachment of the envelope to the pad; and

Figure 6 is a view, partly in cross-section, of the shoulder portion of the garment, the pad, and the pad envelope situated on the shoulder of the wearer.

Referring to Figures 1 and 2, a sheet of flexible material 1, for example, the textile fabric of a garment at the shoulder portion, is shown in Figure 1 at its underface. A pad 2 is secured, as by stitching, at 3, at one or more points along a line extending transverse of the pad to the garment fabric. The pad may be of any suitable construction, for example, as illustrated at 4, having loose cotton batting or other fibrous mass, which is preferably enclosed by a fabric cover 5. If desired, the mass of fibers comprising the pad

4 may be a compacted mass which retains its desired shape without the cover 5. The pad may, of course, be made in any of a number of ways, as by superimposing several layers of fabric, cutting them to the desired shape, and securing them in any desired manner, as by sewing, adhering, or other methods familiar to those skilled in the art. The fastening or fastenings 3, in their simplest form, comprise one or more stitches along a line transverse of the pad 2, thereby leaving the ends 6 and 7 of the pad loose and unattached with respect to the garment portion 1. Other fastening or attaching means may be conveniently used, such as rivets, snap fasteners, and other attaching elements known in the textile and clothing arts. The line along which the fastenings 3 are made may be either a straight or curved line, but it is preferable that it be intermediate the ends of the pad in order to permit the pad to be folded, as shown in Fig. 4, to

50

accommodate the envelope. The fastening line may be diagonal, or longitudinally transverse, if desired, instead of laterally transverse as shown in Figures 1 and 3. The general contour of the pad may be of any desired shape to afford practical or ornamental cushioning of the garment, and is illustrated in the drawing, for the sake of convenience, as having a generally triangular contour having at least one of the sides somewhat curved. The shape may, of course, be circular, ovate, semicircular, rectangular, or otherwise. The thickness of the pad is preferably greatest at the center portion and is reduced progressively toward the edges, or it may be uniform in whole or in part, or it may be thicker at an edge or edges. The edges of the pad are of curved contour, as shown at 6 and 7, although they may be otherwise shaped, and the corners may be either angular or curved.

The envelope 11 generally conforms to the contour of the pad 2. The obverse face of the envelope which is away from the garment 1, and hence normally adjacent the skin of the wearer, preferably comprises a solid uninterrupted surface, although perforations or other ventilating means may be provided, if desired. The reverse face of the envelope is provided with an opening, preferably a slit or slot 12 which has opposed edges 13 and 14. The edges 13 and 14, in the normal position, when the envelope is flat and before attachment to the pad, may be contiguous to each other to form a normally closed slit or slot, or they may be separated to provide an open slot. The outer edges of the envelope are normally closed to join the obverse and reverse faces in the shape of an envelope, and the envelope is preferably slightly larger than the pad 2. The length of the slit or slot 12 is preferably sufficient to accommodate the width of that portion of the pad 2 which it traverses, in order to provide for easy application of the envelope to the pad. The location of the slot 12 is selected to conform to the line along which the fastening or fastenings 3 of the pad to the garment occur.

In applying the envelope 11 to the pad 2, the pad is folded along the line containing the fastening 3, so that the ends 6 and 7 of the pad are brought together in contact or proximity with each other. The envelope 11 is similarly folded along the line of the slot 12, thereby opening the slot on the convex side of the bend and providing an initial receptacle for passage of the contiguous ends 6 and 7 of the pad. After the ends of the pad have entered the opening 12, they are separated so that one end tends to travel along the channel or pocket provided by one side of the envelope, and the other end travels along the other side pocket of the envelope provided by the bend in the envelope, as shown in Figure 4. When the envelope is fitted over the pad to the position shown in Figure 5 the combination of the pad and envelope is ready for wear, and the final position of the pad on the shoulder is shown in Figure 6. The edges 13 and 14 of the envelope surrounding the pad are in close proximity with each other when the envelope is in use, as shown in Figure 6, with the result that almost the entire area of the surface of the pad is encased within the envelope, the only exception being a small slit or slot 12 which accommodates the fastenings 3 connecting the garment 1 and the pad 2. The pad is thus entirely protected from contact with

the skin of the wearer, and hence perspiration cannot contact or enter the shoulder pad.

It is preferable that the envelope be made of moisture-proof material, such as rubber or thin, flexible material, and for ornamental reasons it is often desirable that the material of the envelope be transparent or translucent. The envelope may be readily removed or replaced at any time, suitable to the convenience of the wearer.

Although the invention has been illustrated and described with respect to a shoulder pad for a garment, it is to be understood that the invention is susceptible of many other embodiments and that the protection afforded of the invention is limited only by the scope of the appended claims.

What is claimed is:

1. In combination, a sheet of flexible material, a cushioning pad, and an envelope for said pad, said pad being secured by a fastening along a transverse line on one of the faces thereof to said sheet and having unattached portions extending from either side of said line, said envelope conforming generally to the contour of said pad and having a slot disposed on one face of said envelope corresponding to the width of said pad except along said slot, said envelope enclosing said pad, and said fastening extending through said slot.

2. In combination, a garment, a cushioning pad, and an envelope for said pad, said pad being secured by a fastening along a transverse line on one of the faces thereof to said garment and having unattached portions extending from either side of said line, said envelope conforming generally to the contour of said pad and having a slot disposed on one face of said envelope corresponding to the width of said pad except along said slot, said envelope enclosing said pad, and said fastening extending through said slot.

3. In combination, a garment having a shoulder portion, a shoulder pad, and an envelope for said pad, said pad being secured by a fastening along a transverse line on one of the faces thereof to said shoulder portion and having unattached portions extending from either side of said line, said envelope conforming generally to the contour of said pad and having a slot disposed on one face of said envelope corresponding to the width of said pad except along said slot, and said fastening extending through said slot.

4. In combination, a sheet of flexible material, a flexible cushioning pad, and a flexible envelope for said pad, said pad being secured by a fastening along a transverse line on one of the faces thereof to said sheet and having unattached portions extending from either side of said line, said envelope conforming generally to the contour of said pad and having a slot disposed on one face of said envelope corresponding to the width of said pad, said envelope enclosing said pad except along said slot, and said fastening extending through said slot.

5. In combination, a sheet of flexible material, a flexible cushioning pad, and a flexible envelope for said pad, said pad being secured by a fastening along a transverse line on one of the faces thereof to said sheet and having unattached portions extending from either side of said line, said envelope conforming generally to the contour of said pad and having a slot disposed on one face of said envelope corresponding to the width of said pad, said envelope enclosing said pad except along said slot, said fastening extending through

said slot, and said pad being adapted for bringing the unattached portions thereof together to pass through said slot in the envelope.

6. In combination, a garment, a cushioning pad, and an envelope for said pad, said pad being secured by a fastening along a transverse line on one of the faces thereof to said garment and having unattached portions extending from either side of said line, said envelope conforming generally to the contour of said pad and having a slot disposed on one face of said envelope corresponding to the width of said pad except along said slot, said envelope enclosing said pad, said fastening extending through said slot, and said pad being adapted for bringing the unattached portions thereof together to pass through said slot in the envelope.

7. In combination, a garment having a shoulder portion, a cushioning shoulder pad, and an envelope for said pad, said pad being secured by a fastening along a transverse line on one of the faces thereof to said shoulder portion and having unattached portions extending from either side of said line, said envelope conforming generally to the contour of said pad and having an opening disposed on one face of said envelope corresponding to the width of said pad, said envelope enclosing said pad except along said opening, said fastening extending through said opening and said pad being adapted for bringing the unattached portions thereof together to pass through said opening in the envelope.

8. A protective envelope, for a garment pad centrally attachable to a garment, comprising thin flexible material having the general contour of the pad to be protected and having a slot extending transversely across one face, said slot being adapted to accommodate entry of unattached portions of the pad, and means for holding said envelope in place around said pad which means comprise the envelopment of said pad by said envelope.

5 9. A protective envelope, for a garment pad centrally attachable to a garment, comprising thin flexible material having the general contour of the pad to be protected and having a slot extending transversely across one face, said slot being adapted to accommodate entry of the unattached portions of the pad when said envelope is folded, and said slot in the normally unfolded position remaining open for the accommodation 15 of means for attaching the pad to the garment.
